UNITED STATES PATENT OFFICE.

EDWARD W. LOCKENVITZ, OF BLOOMINGTON, ILLINOIS.

SELF-CLEANING SPARK PLUG.

Application filed November 24, 1926. Serial No. 150,394.

My invention relates to self cleaning spark plugs for gasoline engines, and has for its object to provide a means whereby a spark plug of the type described may be cleaned 5 in an automatic manner induced by the drawing in and compression of the charge in the cylinder of the engine.

Another object of my invention is to provide such a device which shall be easy to 10 manufacture and simple in operation and maintenance.

With the above and other objects in view, my invention consists in the combination and arrangement of parts hereinafter described and claimed, it being understood that, within the scope of what is claimed, changes may be made in the precise embodiment shown without departing from the spirit of the invention.

20 In the drawing:

Figure 1 is an elevation of my invention.

Figure 2 is a sectional view thereof.

Figure 3 is an end view thereof.

Figure 4 is a section along the line 4—4 25 of Figure 2.

Referring now more particularly to the drawings, a spark plug body and shell of ordinary construction is provided, the same comprising a metallic, shell 1, having a nut 2 threaded thereinto; a porcelain 3 is 30 adapted to be positioned, in the said shell 1 by the said nut 2, the copper gaskets 11 and 12 being provided to take care of the difference in expansion of the porcelain and the shell as is usual in such constructions.

A central electrode 9 is concentrically mounted in the porcelain 3, and adapted to project through the said porcelain 3 and outwardly the shell 2; a chamber 13 is 35 provided between the end of the porcelain 3 and the lower end of the shell 2 and a vibrating element 4 of insulating material is slidably mounted concentrically the said central electrode 9 and adapted to vibrate 40 within the said chamber 13. A plurality of dependent pins, as at 10, are provided around the periphery of the bottom of the shell 2; a metallic bottom electrode 5 is 45 slidably mounted concentrically the central electrode 9 on the said pins 10, being restrained thereon by any suitable means, such as the heads 14 provided on the said pins 10; the said bottom electrode 5 is adapted 50 to vibrate on the said pins 10. An aperture

16 is provided concentrically the central 55 electrode 9 in the said bottom electrode 10 suitably to pass the said central electrode 9 therethrough, thereby forming a spark gap between the edge of the said aperture 16 and the surface of the said central electrode 9. A nut 7 is threaded to the said central electrode 9 and a washer 8 is provided suitably to hold the said electrode 9 in position in the said porcelain 3. An electrode nut 6 is threaded to the said electrode 9 suitably to receive an electrical conductor in a manner well known to those skilled in the art. The shell 1 serves to form a part of the electrical circuit of the spark plug when the plug is mounted on the engine 70 (not shown) in a manner usual to the art. In the use of my invention, the alternate drawing in and compression of the charge in the cylinder of the engine (not shown) will cause the vibrating element 4 to reciprocably vibrate on the said central electrode 9 within the chamber 13 so as to thereby cause any carbon that may be lodged upon the said central electrode 9 to be scraped 75 and shaken off. At the same time, the said bottom electrode 5 is adapted to vibrate upon the pins 10, along the axis of the said central electrode 9, whereby any carbon that may accumulate upon the wall of the aperture 16 will be shaken off, and in a like manner 80 the contact between the pins 10 and the bottom electrode 5 will be kept clean, thereby accomplishing the purpose of my invention. It is obvious that the bottom electrode 5 will prevent the vibrating element 4 from 85 dropping out of the spark plug.

I claim:

The combination with a spark plug embodying a ground shell having a plurality of ground pins depending from its lower 95 annular end, an annular bottom electrode slidably mounted on said pins, a dielectric core within the shell, the same being of less length than the shell, thereby providing a chamber between the lower ends of the core 100 and shell, and a central electrode extended through the said core with its lower end depending below the lower end of the shell, of a dielectric vibrating element slidably mounted upon the lower end of the central 105 electrode within the said chamber.

In testimony whereof I affix my signature.

EDWARD W. LOCKENVITZ.
